CLAIM

The ornamental design for a portable water treatment device as shown and described.

DESCRIPTION

FIG. 1 is a top, front, right side perspective view of a portable water treatment device showing our new design; FIG. 2 is a right side elevation view thereof; FIG. 3 is a left side elevation view thereof; FIG. 4 is a rear elevation view thereof; FIG. 5 is a front elevation view thereof; FIG. 6 is a top plan view thereof; FIG. 7 is a bottom, plan view thereof; FIG. 8 is a front elevation view showing the portable water treatment device of FIG. 1 in an alternate position in an environment of use; FIG. 9 is a top, rear, right side perspective view of the portable water treatment device of FIG. 1; and, FIG. 10 is a top, front, left side perspective view thereof. Broken lines in FIGS. 1–7 and 9–10 illustrate portions of the portable water treatment device that form no part of the claimed design. Broken lines in FIG. 8 illustrate environment and portions of the portable water treatment device that form no part of the claimed design.
